UNITED STATES PATENT OFFICE

CHARLES K. HEISTAND, OF EPWORTH, MISSOURI

COMBINED COIN HOLDER AND LETTER CLAMP

Application filed May 13, 1930. Serial No. 451,982.

This invention relates to a device which may be termed a combined coin holder and letter clamp, and which will be found especially useful in rural districts whereby letters and the like, as well as money may be placed in a convenient location for the mail carrier.

Broadly, the invention consists in the provision of a device of this character including a pair of spring jaws between which the letters or other mail may be clamped, and in addition, a coin holder carried by one of the jaws normally closed through the medium of the letters clamped between the jaws.

15 Other objects and advantages of this invention will become apparent during a study of the following description, taken in connection with the accompanying drawings, wherein:

20 Figure 1 is a top plan view of the device, the same being shown with a letter clamped between the jaws thereof,

Figure 2 is a side elevational view thereof,

25 Figure 3 is a top plan view of the jaw and money holder carried thereby,

Figure 4 is an end elevational view of the device.

With reference more in detail to the drawings, it will be seen that my device comprises a substantially U-shaped handle comprising a pair of substantially coextensive legs 5 and 6 respectively. At the crown portion thereof, the wire from which the handle is formed is suitably coiled to provide what may be

30 termed a spring 7, the purpose of which will be hereinafter made manifest. The leg 6 at its free end is bent laterally and then rearwardly and inwardly and then secured to itself whereby to provide at the end of the leg 6 a substantially triangular shaped jaw 8.

35 9 designates a coin receiving receptacle opened at its top. The receptacle 9 is substantially triangular in cross section and is formed from wire mesh or any other suitable material. At its upper edge, the receptacle 9 is suitably secured, as by welding or any other suitable means to the jaw 8. It will be noted that the receptacle 9 and jaw 8 conform in configuration.

40 The leg 5 of the handle at its forward

end portion is bent somewhat in the manner of the leg 6 to provide a substantially triangular shaped jaw 10 for cooperation with the jaw 8 whereby one or more letters L may be clamped between the jaws. In this connection, it will be seen then the letters L or any other such mail may be utilized for constituting a closure for the coin receptacle 9. The jaws are normally maintained closed, or in clamping relation through the medium of the spring 7 as is apparent.

45 It may be also well to mention here, that the jaw 10 at the forward end thereof is bent upwardly and outwardly intermediate the sides of the jaw to provide a raised forwardly extending projection 11.

50 From the foregoing, it will be apparent that when the letters L are disposed between the jaws 8 and 10 the letters will be securely clamped therebetween and extend over the top of the coin receptacle 9 closing the receptacle 9 and thus preventing loss of the contents of the receptacle.

55 It may be also noted, that at the widest end thereof the jaw 10 is of a greater width than the jaw 8 so that the sides of the jaw 10 at the forward end of the jaw will overlap the adjacent sides of the receptacle 9 when no letters are placed between the jaws. This arrangement further provides for and insures 60 the clamping of the letters between the jaws in such a manner as to provide a tight closure for the receptacle 9.

65 The entire device may be suspended from a suitable support or the like at the end of a chain C, said chain at its free end being provided with a spring clasp 12 of conventional structure engaging the spring 7 as clearly suggested in Figures 1 and 2.

70 It is thought that from the foregoing description taken in connection with the accompanying drawings a clear understanding of the use, construction and advantages of an invention of this character will be had by those skilled in the art without a more detailed description thereof.

75 Even though I have herein shown and described the preferred embodiment of my invention, it is to be understood that the same is susceptible to changes in the details of con-

struction, materials used and the like and that accordingly I do not limit myself beyond the spirit of the claims hereunto appended, or the requirements of the prior art.

Having thus described my invention, what I claim as new is:

1. In a device of the class described, a substantially U-shaped handle formed of wire and provided at the crown portion thereof with a spring, the legs of said U-shaped handle at their free ends respectively terminating in a jaw, said spring normally urging the jaws toward one another for clamping an article between said jaws, a coin receiving receptacle carried by one of said jaws and adapted to be closed through the medium of the article clamped between said jaws.

2. In a device of the class described, a substantially U-shaped handle formed of wire and provided at the crown portion thereof with a spring, the legs of said U-shaped handle at their free ends respectively terminating in a jaw, said spring normally urging the jaws toward one another for clamping an article between said jaws, a coin receiving receptacle carried by one of said jaws and adapted to be closed through the medium of the article clamped between said jaws, each of said jaws being of substantially triangular frame like structure, and said receptacle being substantially triangular in cross section.

3. In a device of the class described, a substantially U-shaped handle formed of wire and provided at the crown portion thereof with a spring, the legs of said U-shaped handle at their free ends respectively terminating in a jaw, said spring normally urging the jaws toward one another for clamping an article between said jaws, a coin receiving receptacle carried by one of said jaws and adapted to be closed through the medium of the article clamped between said jaws, each of said jaws being of substantially triangular frame like structure, and said receptacle being substantially triangular in cross section, said receptacle being formed of wire mesh, and said spring member constituting means whereby the entire device may be suspended from a support.

4. In a device of the character described, a pair of complementary jaws, means normally urging said jaws into clamping relation with respect to one another, and a receptacle mounted on one of said jaws and having an open side adapted to be closed by the article clamped between said jaws.

In testimony whereof I affix my signature.
CHARLES K. HEISTAND.
